J. KARP.
WATER HEATER.
APPLICATION FILED AUG. 20, 1917.

1,281,388.

Patented Oct. 15, 1918.

By his Attorneys

Inventor
Jacob Karp.
Edgar State & Co.

UNITED STATES PATENT OFFICE.

JACOB KARP, OF BROOKLYN, NEW YORK.

WATER-HEATER.

1,281,388.

Specification of Letters Patent. Patented Oct. 15, 1918.

Application filed August 26, 1917. Serial No. 187,067.

To all whom it may concern:

Be it known known that I, JACOB KARP, a citizen of the United States, and residing at Brooklyn, in the county of Kings and State of New York, have invented certain new and useful Improvements in Water-Heaters, of which the following is a specification, such as will enable those skilled in the art to which it appertains to make and use the same.

10 This invention relates to water heaters and hot water supply devices or apparatus, and particularly to apparatus of this class known as kitchen boilers or heaters; and the object thereof is to provide an improved water heater of this class having an improved circulation and constructed and arranged with a view to efficient and economic service.

15 The invention is fully disclosed in the following specification, of which the accompanying drawing forms a part, said drawing being a side view of my improved water heating apparatus or kitchen boiler.

20 In the accompanying drawing the separate parts of my improvement are designated by suitable reference characters and, generally speaking, my improved kitchen boiler or water heating apparatus is of the same general form as that of other devices of its class. In the practice of my invention, I provide a 25 device or apparatus of the class specified, comprising a vertical top boiler member *a* having a depending skirt portion *a*² in the top portion of which are circularly arranged apertures *a*³ and the skirt portion *a*² is mounted on a suitable support *b*, comprising a base member *b*² having a tubular standard *b*³, the top of which is provided with a head *b*⁴ provided with radially arranged and, upwardly curved arms *b*⁵ which are connected with the skirt portion *a*² of the boiler in any desired manner.

30 A gas supply pipe *c* is connected with the tubular standard *b*³ and provided with a valve *c*², and connected with said tubular standard *b*³ is a Bunsen burner attachment *d* of any preferred construction having a burner *d*² also of any preferred construction, and the burner *d*² is flush with or fits in the bottom of the skirt portion *a*² of the boiler.

35 The skirt portion *a*² of the boiler forms a chamber *e*, and mounted in one side portion of said chamber at the bottom thereof is a coupling head *f*, and in the top portion of said chamber and preferably at the opposite side thereof is another coupling head *f*², and

these coupling heads *f* and *f*² are connected by a plurality of circulating coils *f*³ and a pipe *g* is connected with the coupling head *f* as shown and extends upwardly through the coils *f*³ and is connected with the bottom *a*⁴ 60 of the boiler *a* centrally thereof and communicates with said boiler.

40 A water circulating pipe *h* is connected with the top coupling head *f*² by a coupling *h*² passed through the skirt *a*², and the pipe *h* extends upwardly and is connected, in the form of construction shown, with a three-way coupling *h*³ with which is also connected a pipe *h*⁴ which communicates with the boiler *a* through the top head thereof and a 70 hot water supply pipe *h*⁵ is also connected with the coupling *h*³. The boiler *a* is also provided with a cold water supply pipe *i* with which is connected a supplemental cold water supply pipe *i*² which communicates with the 75 boiler *a* through the top head thereof and said pipe *i*² is preferably extended downwardly in said boiler to a suitable distance, and the coupling head *f* is provided with a coupling which passes through the skirt *a*² 80 and with which is connected a water discharge and drainage pipe *j* having a valve *j*² and it will also be understood that the pipes *h*, *h*⁴, *h*⁵ and *i* may be provided with 85 any and all necessary valves.

45 As hereinbefore stated the burner *d*² may be of any desired construction and the fuel may be supplied thereto in any preferred way, and the operation will be readily understood from the foregoing description 90 when taken in connection with the accompanying drawing and the following statement.

50 In the use of my improved apparatus cold water is supplied through the pipe *i*, in the usual manner, and this water fills, or partially fills, the boiler *a* and passes downwardly through the pipe *g* into the bottom coupling head *f* and flows upwardly through the coils *f*³ 100 into the top coupling head *f*² and through the pipe *h* back into the boiler through the pipe *h*⁴ and the water also flows through the pipe *h*⁵ into the hot water supply pipe *h*⁵ by which the hot water may be carried to any desired point.

55 Whenever it is necessary or desired to clean or drain the boiler, this operation may be performed through the pipe *j* in the usual manner.

Having fully described my invention, what 110

I claim as new and desire to secure by Letters Patent, is:—

1. In an apparatus of the class described, a vertically arranged boiler provided at the bottom thereof with a depending skirt portion open at the bottom and the top of which is provided with a plurality of openings, said skirt portion forming a fire chamber at the bottom of the boiler, a burner mounted 5 in the bottom of said chamber, coupling heads mounted in the top and bottom portions of the fire chamber and provided with coupling members which pass outwardly through the walls thereof, a plurality of 10 water circulating coils mounted in said chamber one within the other and the ends of which are connected with said coupling heads and a pipe connected with the bottom coupling head and extending vertically and centrally through the inner coil and communicating with the bottom of the boiler.
2. In an apparatus of the class described, a vertically arranged boiler provided at the bottom thereof with a depending skirt portion open at the bottom and the top of which is provided with a plurality of openings, said skirt portion forming a fire chamber 15 20 25

at the bottom of the boiler, a burner mounted in the bottom of said chamber, coupling heads mounted in the top and bottom portions of the fire chamber and provided with coupling members which pass outwardly through the walls thereof, a plurality of water circulating coils mounted in said chamber one within the other and the ends of which are connected with said coupling heads, a pipe connected with the bottom coupling head and extending vertically and centrally through the inner coil and communicating with the bottom of the boiler, a water circulating pipe connected with the top coupling head through its coupling member and another pipe connected with the bottom coupling head through its coupling member.

In testimony that I claim the foregoing as my invention I have signed my name in presence of the subscribing witnesses this 16th day of August 1917.

JACOB KARP.
